UNITED STATES PATENT OFFICE.

WILLIAM SEYBOURNE BAILEY AND PATRICK HENRY MURRAY, OF HONG-KONG, CHINA.

HANDLE FOR CANS, DRUMS, OR SIMILAR RECEPTACLES.

SPECIFICATION forming part of Letters Patent No. 650,773, dated May 29, 1900.

Original application filed September 27, 1899, Serial No. 731,864. Divided and this application filed January 16, 1900. Serial No. 1,678. (No model.)

To all whom it may concern:

Be it known that we, WILLIAM SEYBOURNE BAILEY and PATRICK HENRY MURRAY, engineers, subjects of the Queen of Great Britain, 5 residing at Hong-Kong, China, have invented a certain new and useful Improvement in Handles for Cans, Drums, or Similar Receptacles, (forming a division of the application, Serial No. 731,864, filed September 27, 1899,) 10 of which the following is a specification, reference being had to the accompanying drawings, in which—

Figure 1 is a side view of a handle and ferrule ready to be secured to a can, drum, or similar receptacle. Fig. 2 is a plan of part of the top of the can, drum, or similar receptacle prepared for the attachment of the handle thereto; and Fig. 3 is a transverse section, drawn to an enlarged scale, showing a handle 20 secured to the can, drum, or the like.

This invention relates to the securing of handles to cans, drums, or like receptacles for containing oil or other liquids or substances. The method is described and claimed in the 25 above-named application, Serial No. 731,864, and the present divided application is for the purpose of covering the product of said method. Handles for such receptacles are usually made of wire bent to a suitable shape 30 and are pivotally connected to the receptacle in such a manner that they can be turned down close to the top thereof to facilitate the packing or storing of the receptacles or can be turned into an upright position when it is 35 desired to carry the receptacle by means of the handle. Heretofore these handles have been secured to the top of the receptacle by means of a metal plate arched or raised along the middle, so that when this arched or raised 40 part is placed over the lower part of the handle the parts of the said plate on either side of the arched or raised part thereof will lie flatly against the top of the receptacle, to which they are then secured by means of solder.

45 This old method of securing the handles is not only a crude and clumsy one, but it involves the use of an unnecessarily - large amount of solder—that is to say, of more solder than is really necessary to enable the handle to sustain the weight of the receptacle

when full. It is also apt to cause a wasteful application of the solder, and consequently the cost of the solder becomes an important item in the securing of handles to thousands of receptacles by this old method.

55

Now the object of the present invention is to facilitate and expedite the operation of securing the handles to the receptacles, while effecting a considerable economy in the use of the solder and improving the appearance 60 of the finished receptacle.

According to the improved method the top of the can, drum, or other receptacle is made with raised portions so located relatively to each other as to form between them a groove 65 or channel of sufficient width to receive a tube or ferrule, which is fitted on or formed about the lower part of the handle, so that the said handle can turn freely in it. When this tube or ferrule is placed in or partly in the said 70 groove or channel between the raised portions of the top of the receptacle, it can be firmly secured to the latter by means of two very small pieces or quantities of solder, one at each side of the said tube or ferrule. If desired, the said tube or ferrule after being fitted on or formed about the lower part of the handle is soldered to the ordinary flat top of the can, drum, or other receptacle, or instead of making the top with raised portions 75 80 it is made with a groove or depression, into which the said tube or ferrule can be placed and soldered; but it is more advantageous to make the top of the receptacle with raised portions, as above described, which can be 85 effected by stamping or in any other convenient manner.

Referring to the accompanying drawings, *a* is the top of any suitable can, drum, or other receptacle.

90

b is the wire handle.

c is a metal tube or ferrule which is formed by bending a piece of tin or sheet metal around the lower part of the handle *b*, so that its longitudinal edges meet or nearly meet, or, 95 if desired, so that the said edges overlap each other more or less.

The top *a* of the receptacle is made with ridges or raised portions *d e*—for example, by stamping up the metal, as shown—and in 100

the channel formed between these ridges or raised portions the said tube or ferrule is placed with its adjacent or overlapping edges lowermost. Solder is then applied at *fg*, Fig. 3, so as to firmly unite the said tube or ferrule to the said ridges or raised portions *d e*. It is evident that these raised portions of the top *a* can, if desired, be made of less width or shallower, or the top *a* may be made without such raised portions or with a groove or depression to receive the said tube or ferrule; but it is preferable to make it with raised portions somewhat like those shown in Fig. 3.

What we claim is—

- 15 1. The combination of a wire handle, a metallic surface, as the top of a can, drum or the like, having a groove or channel, and a tube or ferrule mounted on the lower part of said handle, fitted into said groove or channel and 20 soldered thereto, substantially as described.
2. The combination of a wire handle, a me-

tallic surface, as the top of a can, drum or the like, having parallel ridges or raised portions, and a tube or ferrule mounted on the lower part of said handle, fitted in the groove or 25 channel between said ridges or raised portions, and soldered to said ridges or raised portions respectively, substantially as described.

3. The combination of a metallic surface, a groove or channel formed by raising part of the said surface, a wire handle, and a tube or ferrule mounted on the lower part of said handle and soldered in said groove or channel, substantially as described. 30

In witness whereof we have hereunto set our hands in presence of two witnesses.

WILLIAM SEYBOURNE BAILEY.
PATRICK HENRY MURRAY.
